EDUCATIONAL TOY AUTOMOBILE

Archibald Carl Young, St. Louis, Mo.

Application December 4, 1948, Serial No. 149,978

Term of patent 14 years

(Cl. D34—15)

To all whom it may concern:

Be it known that I, Archibald Carl Young, a citizen of the United States, residing at St. Louis, Missouri, have invented a new, original, and ornamental Design for an Educational Toy Automobile, of which the following is a specification, reference being had to the accompanying drawing, forming part hereof.

Figure 1 is a side elevation of an educational toy automobile, showing my new design.

Figure 2 is a top view of the same toy automobile.

Figure 3 is a front view of the same toy automobile.

Figure 4 is a perspective view of the same toy automobile.

The opposite side of the toy is similar to that shown.

The characteristic features of my design are shown in full lines in the drawings.

I claim:

The ornamental design for an educational toy automobile, substantially as shown and described.

ARCHIBALD CARL YOUNG.
